US00D776296S

(12) **United States Design Patent** (10) **Patent No.:** **US D776,296 S**
(45) **Date of Patent:** **** Jan. 10, 2017**

(54) **ADAPTER**

(71) Applicants: **Charles River Laboratories, Inc.**,
Wilmington, MA (US); **ReaMetrix Inc.**,
San Carlos, CA (US)

(72) Inventors: **Norman R. Wainwright**, Johns Island,
SC (US); **Dana M. Nutter**, Charleston,
SC (US); **Eric Stimpson**, Charleston,
SC (US); **Al Fuchs**, Charleston, SC
(US); **Thomas Preidel**, Uslar (DE);
